UNITED STATES PATENT OFFICE.

FRED H. FERRIS, OF MECHANICSVILLE, NEW YORK.

DESIGN FOR AN ARM FOR FLAGSTAFF-HOLDERS.

SPECIFICATION forming part of Design No. 29,228, dated August 16, 1898.

Application filed June 2, 1898. Serial No. 682,407. Term of patent 14 years.

To all whom it may concern:

Be it known that I, FRED H. FERRIS, a citizen of the United States, residing at Mechanicville, in the county of Saratoga and State 5 of New York, have invented and produced a new and original Design for an Arm for Flagstaff-Holders; and I do hereby declare the following to be a full, clear, and exact description of the same, reference being had to 10 the accompanying drawings, forming a part thereof.

In the drawings, Figure 1 is a plan view of an arm for flagstaff-holders embodying my design. Fig. 2 is a side view of the same.

15 As illustrated in the drawings, B represents the body portion of the arm, which has for its essential features an upper surface b' concave in cross-section and inclined from each end toward a central enlargement C, 20 the upper surface of which is also concave in

cross-section and provided with a transverse opening b . The upper marginal edges B^2 of the arm are provided with oppositely-disposed flanges C^2 and C' , having curved inner walls. Longitudinal ribs D are formed on 25 the under side of the arm and extend from the central enlargement C to the respective ends of the arm. The supporting end of the arm is provided with a vertical flange A, having a transverse opening a . 30

Having thus described my invention, what I claim is—

The design for an arm for a flagstaff-holder, substantially as shown and described.

In testimony whereof I affix my signature 35 in presence of two witnesses.

FRED H. FERRIS.
